To all whom it may concern:

Be it known that I, Lee T. Bordner, a citizen of the United States, residing at Los Angeles, in the county of Los Angeles and State of California, have invented a new, original and ornamental Design for a Switch Handle, of which the following is a specification, reference being had to the accompanying drawing, forming part thereof.

In the drawing

Fig. 1 is a front perspective view of the switch handle, showing my new design;

Fig. 2 is a rear perspective view thereof;

Fig. 3 is a top plan view thereof; and

Fig. 4 is a fragmentary perspective view, on a slightly enlarged scale, of the handle portion only.

I claim:

The ornamental design for a switch handle, as shown.
